UNITED STATES PATENT OFFICE.

RICHARD E. ROSEWARNE, OF COVINGTON, KENTUCKY, ASSIGNOR OF ONE-HALF TO
EDWARD F. PETERS AND WILLIAM PETERS, BOTH OF CINCINNATI, OHIO.

CUTTER HEAD FOR CIGARETTE MACHINES.

Application filed April 3, 1922. Serial No. 549,349.

To all whom it may concern:

Be it known that I, RICHARD E. ROSEWARNE, a citizen of the United States, and a resident of Covington, in the county of 5 Kenton and State of Kentucky, have invented certain new and useful Improvements in Cutter Heads for Cigarette Machines, of which the following is a full, clear, and exact description, reference being had to the 10 accompanying drawings, forming part of this specification.

My invention relates to cutting mechanism for severing predetermined lengths of a continuously moving stock of material 15 and has special relation to such cutting devices when applied to sever into fixed lengths the continuously moving cigarette rod formed on the cigarette machine in which the paper covering is wound around 20 the rod of tobacco and the rod delivered to the severing mechanism continuously to be ultimately severed into individual cigarettes of the desired uniform length.

For such cutting mechanism it is obviously necessary that the cutter shall be moved not only transverse the rope, but also lengthwise synchronously with the advance 25 of the stock. The usual methods to accomplish these movements have been to provide 30 for an orbital movement of the knife at right angles to the lengthwise movement and to mount the cutting knife with its transverse actuating devices on a proper carriage and to shift the entire carriage by 35 crank throw or cam devices which must carry the weight of the cutter mechanism, necessarily causing a shock and undesired vibrations with each reciprocation of the carriage, and obviously placing a serious 40 limitation in the speed with which the mechanism can be operated, in addition to causing undue wear and necessitating heaviness and weight of parts to withstand the shocks.

It is the object, therefore, of my invention to furnish a construction of a minimum number of parts, in which the highest speed may be maintained without shocks and jars due to reciprocation, and in which the usual weight of the parts is avoided with 45 minimum wear and with readily renewable wearing parts.

One of the important features of my invention consists of the construction in which

the necessity for the reciprocation of any carriage for the cutting mechanism is obviated and the knife is given an orbital movement parallel with and at the same speed as the longitudinal movement of the cigarette rod, so that with a single throw of the actuating crank, the transverse and longitudinal movement of the cutter is attained. 55

Another feature of importance is that the cigarette tube through which the cigarette rod is fed is the only part of the mechanism which requires reciprocation, and this tube 60 may be made exceedingly light so that there is no appreciable shock or jar in the operation and a very high speed may be attained without detriment or undue wear. 65

Another feature of improvement consists 70 in the use of the connecting rod through which the cutting knife is given its orbital movement for connection with the cigarette tube to obtain the reciprocating movement and the location of this coupling near the 75 center of the tube so as to obtain a substantially vertical transverse movement for the knife at its cutting edge by controlling the angular position of the knife cutter head on the connecting rod. 80

Another feature of the invention relates to the adjustment of the knife relative to the cut-off tube opening, so as to make the cut at the tangential angle on the orbit of the actuating crank required for the length of 85 the cigarette and the longitudinal movement of the cigarette rod. 85

Still another feature relates to the construction of the knife ledger of such a size that the cutting knife may be adjusted at its 90 lower edge to match for automatic operation.

These features and others will be more specifically referred to in the course of the description that follows, in connection with the drawings, in which— 95

Figure 1 is a side elevation of the right side of the machine;

Figure 2 is a top plan view;

Figure 3 is a rear elevation;

Figure 4 is a side elevation of the left 100 side of the machine illustrating the driving mechanism;

Figure 5 is a side and front end elevation of the cutter crank shaft;

Figure 6 is a plan and front elevation 105 of the connecting rod or pitman upon which

the cutter knife head is mounted and which connects the crank shaft with the reciprocating cigarette tube;

Figure 7 is a side elevation and plan view of the cutter head;

Figure 8 is a perspective view of the machine, with a portion of the bed broken away.

Mounted and guided to slide horizontally 10 in the bed frame 1 of the machine is the cigarette tube 2 through which the severed cigarettes are fed. This tube is provided at its front end with an angular extension 3 upon which is mounted the bell mouth receiver 4, through which the cigarette rod is fed continuously at a predetermined rate of speed from the cigarette machine, not shown. The inner end of this bell mouth carries the cutting off ledger 5 against which 20 the cutting knife acts to sever the cigarettes. The opening in the bell mouth and ledger disk is in exact alignment with the tube 2 with a clearance space 6 for the cutting knife. Clamped on the inner end of 25 the cigarette tube, which projects beyond the frame is a split clamp block 7 tightened by screw 8. This block carries a stud 9 upon which is mounted one end 10^a of a connecting rod or pitman 10 which is at the other end 10^b mounted on the stud 12 projecting eccentrically from the segment disk 13 on the end of the crank shaft 14 suitably journaled in the frame. The connecting rod 10 is formed with an extension 15 projecting upwardly at a slight angle to the longitudinal axis of the rod, and on this extension is adjustably clamped by clamping screw 16 the cutter head 17. This head carries the sleeve 18 in which is journaled the knife shaft 19 upon one end of which is rigidly secured the disk cutter 20 by the nut 21 between washers 22 with the flange 23 on the knife shaft bearing against the end of the sleeve. On the other end of the knife shaft is keyed the sheave 24 by means of which the knife is rotated at a very high rate of speed by a belt 24^a from the driving sheave 25. This driving sheave is keyed to the sheave shaft 26 journaled in a sleeve 27 40 on the arm 28, which is provided with a split hub 29 clamped over the hub of a speed gear 30 keyed on the main driving shaft 31 of the machine. This speed gear 30 meshes with the pinion 32 keyed on the end of the drive sheave shaft 26, so that the disk cutting knife can be driven at very high speed to effect a clean cut. The arm carrying the drive sheave is secured adjustably on the hub of the gear 30, so that it can be adjusted 45 to tighten the driving belt. The cutter head is also adjustable vertically on the extension by the screw bolt 33, which takes through the boss 34 into the lug 35 on the end of the connecting rod 10.

65 For driving the crank shaft 14 a beveled

pinion 36 is keyed on its opposite end which meshes with the beveled gear 37 keyed on the main shaft 31.

The operation of the machine is as follows.

70 By reason of the fact that the cutter head carrying the disk cutter is mounted on the extension from the connecting rod 10 it is obvious that as the crank shaft 14 is rotated and the stud 12 moves around the center of the longitudinal axis of the crank shaft, that the cutter head and cutter will be raised and lowered in an orbit parallel with the longitudinal axis of the connecting rod and that the cutter will pass the ledger and sever the cigarette rod while moving in a circular path in the same direction that the cigarette tube is moving inasmuch as the connecting rod is coupled to the tube member and gives it reciprocating movement.

75 The cigarette rod fed to the cutter is controlled by a pulley driving a tape belt which envelopes the cigarette rod while the paper is being wrapped around the tobacco. The pulley is formed to embrace a certain 80 number of inches in its circumference and is driven through the main driving mechanism at a constant rate of speed, and the gearing which drives the crank shaft for the cutter head is also driven from this main driving shaft, so that by selecting the proper number of teeth for the crank shaft gear, the number of times in any length of rod the knife is operated will determine the 85 length of each cigarette. The crank shaft will be driven faster with a gear of smaller 90 number of teeth, so that by changing this gear I can change the times of operation 95 of the cutter for the length of cigarette desired.

100 If we assume the mechanism in the position shown in Figure 1, the cutter has just completed its down stroke and as the crank disk 13 is rotating anti-clockwise with the connecting rod 10 connected to the cigarette tube, the cutting disk moves with the cigarette rod at the same speed. The cutter head rocking with the extension on the connecting rod 10 also moves upward on a circular path with the axis of the stud 9 as 105 a center, but remains in substantially vertical position as it passes the ledger and thus in no way interferes with the continuous movement of the cigarette rope. I am 110 able to obtain this vertical position for the knife in its movement through the cigarette rod by reason of the fact that the connecting rod 10 is pivoted to the cigarette tube by the stud 9 at the center of the tube. The 115 cutter therefore in its transverse movement swings on a radius with the tube as a center and therefore it will take a vertical position for its severing operation.

120 When the cutting knife has traversed half of its upward path, the cigarette tube 125

reaches the end of its forward movement and commences its rearward movement, which is maintained until the crank pin 12 reaches its furthest position on the left. The cutting knife during the last quarter of this rotation has moved downwardly in its orbital path and the cutting edge reaches the cigarette rod with a substantially vertical position of the cutting disk at a point about midway of the rotation of the crank pin 12 between its extreme position to the left and its lowermost position. As I have hereto stated the distance apart of the points of severance of the cigarette rod will depend on the speed of the crank disk and as this speed also determines the speed of reciprocation of the cigarette tube, the knife edge of the cutting disk is adjusted in position to intersect the cigarette rod at the angular position of the crank pin circle corresponding to the required length of the cigarettes.

The cut takes place on a tangent to the crank pin circle and as the cigarette rod is moving at a constant rate of speed, when the reciprocation of the cutter is increased this tangent will be more nearly vertical than when the reciprocation of the cutter is decreased. I am able therefore by adjustment of the cutter head vertically to raise or lower the cutting edge of the knife with reference to the ledger disk so as to obtain a vertical cut of the cigarette. After the knife has severed the cigarette rod it will then swing slightly away from the ledger plate and in its upward movement to pass the advancing cigarette rope, it will then be moving longitudinally, somewhat faster than the rod, so that there is no danger of interference.

Having thus described my invention, what I claim as new and desire to secure by Letters Patent, is:—

1. In a severing device for severing into sections continuously moving material, a cutting knife, a mounting for such knife, and means to swing the knife in an orbit transverse and in a plane parallel with the line of travel of the material to be severed, with the orbital center of the knife in alignment with the line of travel of the material.

2. In a severing device for severing into sections continuously moving material, a holder through which the material is advanced, a cutting knife, a mounting for said knife, and means to swing the knife in an orbit transverse and in a plane parallel with the line of travel of the material to be severed, with means for shifting said holder in timed relation to the orbital movement of the cutting knife, and with the orbital center of the knife in alignment with the longitudinal axis of the holder to give a vertical cut.

3. In a severing device for severing into

sections continuously moving material, a cutting disk, a mounting therefor, with means for rotating said disk at a high rate of speed on its own axis and means for swinging the cutting disk while rotating in an orbit transverse and in a plane parallel with the line of travel of the material to be severed, with the orbital center of the disk in alignment with the line of travel of the material to give a vertical cut.

4. In a severing device for severing into sections continuously moving material, a holder through which the material is advanced, a cutting disk, a mounting therefor, with means for rotating said disk at a high rate of speed on its own axis and means for swinging the cutting disk while rotating in an orbit transverse and in a plane parallel with the line of travel of the material to be severed, with means for shifting said holder in timed relation to the orbital movement of the cutting disk, with the center of this movement in alignment with the longitudinal axis of the holder to give a vertical cut.

5. In a severing device for severing into sections continuously moving material, a slidable holder through which the material is advanced, a crank shaft with crank thereon, and a connecting rod coupling the crank and holder, a cutting knife and a cutter head therefor, said cutter head mounted on the connecting rod, whereby the rotation of the crank shaft will simultaneously move the knife in an orbit transverse the holder and in a plane parallel with the slidable holder to sever the material while under continuous lengthwise movement.

6. In a severing device for severing into sections continuously moving material, a slidable holder through which the material is advanced, a crank shaft with crank thereon, and a connecting rod coupling the crank and holder at the center of the longitudinal axis of the holder, a cutting knife and a cutter head therefor, said cutter head mounted on the connecting rod, whereby the rotation of the crank shaft will simultaneously move the knife in an orbit transverse the holder and in a plane parallel with the slidable holder to sever the material while under continuous lengthwise movement.

7. In a severing device for severing into sections continuously moving material, a slidable holder through which the material is advanced, a crank shaft with crank thereon, and a connecting rod coupling the crank and holder, a rotary cutting disk and a cutter head therefor, with means for rotating said disk at a high rate of speed on its own axis, said cutter head mounted on the connecting rod, whereby the rotation of the crank shaft will simultaneously move the cutting disk in an orbit transverse the holder and in a plane parallel with the slidable

holder to sever the material while under continuous lengthwise movement.

8. In a severing device for severing into sections continuously moving material, a 555 slide tube through which the material is advanced, a crank shaft with crank thereon, and a connecting rod extending parallel with the tube for coupling the tube to the crank shaft, an extension on the connecting rod at the crank connection, with a cutter head mounted on said extension, a cutting disk with the shaft therefor journaled in said cutter head at right angles to the axis of the crank shaft, a train of gearing for 10 rotating the cutting disk at a high rate of speed, and a train of gearing for rotating the crank shaft, with a main driving shaft for both sets of gearing, whereby the rapidly rotating cutting disk may be caused to sever the advancing material while moving with and at the same speed therewith.

9. In a severing device for severing into sections continuously moving material, a crank shaft with a crank thereon, a cutting 15 knife and a cutter head therefor, the cutter head pivotally mounted on the crank so as to partake of the rotary movement thereof,

and connection for the cutter head with a relatively fixed pivot to prevent the rotation of the cutter head on the crank, said relatively fixed pivot being located in line with the line of movement of the advancing material, whereby the cutting knife may be actuated in a plane substantially at right angles to the material to be severed during the severing movement.

10. In a severing device for severing into sections continuously moving material, a slide holder through which the material is advanced, a crank shaft with a crank thereon, a cutting knife and a cutter head therefor, the cutter head pivotally mounted on the crank so as to partake of the rotary movement thereof, and a pivotal connection for the cutter head with the slide holder to prevent rotation of the cutter head on the crank, said pivot being located substantially at the longitudinal axis of the holder, whereby the cutting knife may be actuated in a plane substantially at right angles to the material to be severed during the severing movement.

11. In a severing device for severing into sections continuously moving material, a

crank shaft with a crank thereon, a cutting knife and a cutter head therefor, the cutter head pivotally mounted on the crank so as to partake of the rotary movement thereof,

and connection for the cutter head with a relatively fixed pivot to prevent the rotation of the cutter head on the crank, said relatively fixed pivot being located in line with the line of movement of the advancing material, whereby the cutting knife may be actuated in a plane substantially at right angles to the material to be severed during the severing movement.

12. In a severing device for severing into sections continuously moving material, a

crank shaft with a crank thereon, a cutting knife and a cutter head therefor, the cutter head pivotally mounted on the crank so as to partake of the rotary movement thereof,

and connection for the cutter head with a relatively fixed pivot to prevent the rotation of the cutter head on the crank, said relatively fixed pivot being located in line with the line of movement of the advancing material, whereby the cutting knife may be actuated in a plane substantially at right angles to the material to be severed during the severing movement.

13. In a severing device for severing into sections continuously moving material, a

crank shaft with a crank thereon, a cutting knife and a cutter head therefor, the cutter head pivotally mounted on the crank so as to partake of the rotary movement thereof,

and connection for the cutter head with a relatively fixed pivot to prevent the rotation of the cutter head on the crank, said relatively fixed pivot being located in line with the line of movement of the advancing material, whereby the cutting knife may be actuated in a plane substantially at right angles to the material to be severed during the severing movement.

14. In a severing device for severing into sections continuously moving material, a

crank shaft with a crank thereon, a cutting knife and a cutter head therefor, the cutter head pivotally mounted on the crank so as to partake of the rotary movement thereof,

and connection for the cutter head with a relatively fixed pivot to prevent the rotation of the cutter head on the crank, said relatively fixed pivot being located in line with the line of movement of the advancing material, whereby the cutting knife may be actuated in a plane substantially at right angles to the material to be severed during the severing movement.

15. In a severing device for severing into sections continuously moving material, a

crank shaft with a crank thereon, a cutting knife and a cutter head therefor, the cutter head pivotally mounted on the crank so as to partake of the rotary movement thereof,

and connection for the cutter head with a relatively fixed pivot to prevent the rotation of the cutter head on the crank, said relatively fixed pivot being located in line with the line of movement of the advancing material, whereby the cutting knife may be actuated in a plane substantially at right angles to the material to be severed during the severing movement.

16. In a severing device for severing into sections continuously moving material, a
